MINING MACHINE

John R. Cartlidge and Armin O. Bruestle, Cincinnati, Ohio, assignors to The Cincinnati Mine Machinery Company, Cincinnati, Ohio, a corporation of Ohio

Application August 9, 1940, Serial No. 351,996

11 Claims. (Cl. 262—33)

Our invention relates to mining machines and is particularly directed to improvements in the mounting means for the cutter bits or teeth employed in a coal cutting chain.

The mining machines to which these bits or teeth are applied are of that type utilizing an endless chain composed of a series of bit blocks linked together. There is a bit holder for carrying the bit itself which is removably mounted on the bit block and which may be easily removed and replaced for the insertion of new bits as soon as the old ones have become dull. A chain of this type and to which this invention relates is described in Patent No. 2,039,747 issued in the names of Edwin P. Stenger and Armin O. Bruestle.

Our invention specifically relates to a bit holder for use with the old and well known type of bit block having a top surface pierced by an aperture in which the shank of a bit holder is retained by means of a set screw. In this type bit block the bit holder may be reversed so that the cutting edge of the bit may be presented in either direction with reference to the line of the chain.

Inasmuch as the bit holder as well as the bit is subject to a tremendous wear in use it is necessary that it be of extremely rugged construction and be so configured and arranged that removal and replacement in a dark mine is relatively simple.

It is an object of our invention to provide a bit holder which may be used with the conventional type of bit block and which holds the bit extremely firm while in use and at the same time permits easy removal of both the bit holder and the retained bit.

It is a further object of our invention to make a bit holder with reversible parts so the parts may be reversed when worn.

It is a further object of our invention to provide a bit holder which may be shimmed after it is worn in order to retain the same efficiency as a new bit holder.

These and other objects of our invention which will be set forth hereinafter or will be apparent to one skilled in the art upon reading these specifications, we accomplish by that certain construction and arrangement of parts of which we shall now describe an exemplary embodiment. Reference is now made to the drawing which forms a part herein and in which:

Figure 1 is a side elevation of a bit block carrying our novel type of bit holder with a portion cut away to show the construction.

Figure 2 is a section taken along the section line 2—2 of Figure 1.

Figure 3 is a plan view of our novel bit holder and its block as shown in Figure 1.

Figure 4 is a perspective view of the cradle portion of our bit holder.

5 Figure 5 is a side elevation of a modification of the cradle for use with our bit holder.

Figure 6 is a section of Figure 5 taken on the section line 6—6.

Figure 7 is a side elevation of a shim for use with either the cradle shown in Figure 4 or that shown in Figure 5.

Figure 8 is a side elevation of a modified form of our novel bit holder.

Figure 9 is a side elevation of a bit block carrying our novel type of bit holder similar to Figure 1, but with a shim placed between the cradle and the bit block.

Briefly in the practice of our invention, we provide a bit holder having a head with a bit receiving aperture and a projecting shank for insertion into the aperture of the bit block. While the head retains the shank portion of the bit and one end thereof, the opposite end and cutting surface projects beyond the aperture. The shank of the bit holder projects through and the head thereof lies in a cradle which surrounds the shank portion of the head so that an abutment is presented to the lower portion or heel of the cutting face of the bit and the cradle is retained in position by its opposite end abutting the back of the head of the holder.

Referring to the drawing the bit block is indicated at 1 with the bit holding aperture 2 and the retaining set screw 3.

35 Our bit holder has the head 4 with the bit holding aperture 5 cut therein and a pin 6 for contacting the bit and preventing longitudinal movement in one direction. The lower surface of the head 4 is beveled as at 7 and terminates in the shank 8 which projects in the usual manner in the aperture 2 and is retained by the set screw 3.

We provide a cradle 10 having two parallel side bars 11 the inner faces of which are beveled as at 12. The side bars 11 terminate in the abutment 13 at one end and the abutment 14 at the other end. The bit holding abutment 13 has a cut away portion 15 so as to closely contact the cutting face 16 of the bit 17 when the holder is in place.

50 The dimensions and parts are so configured that that the shank 8 of the bit holder is inserted between the side bars 11 until the head 4 slides in the cradle with its beveled bottom edges 7 within but preferably not contacting the bevel 12 of the side bars 11 of the cradle 10. The rear face 4a of

the head 4 abuts against the inner face of the abutment 14 while the notch 15 in the bit abutting end 13 abuts against the face 16 of the bit 17.

By the above construction it is apparent that the bit 17 is prevented from moving longitudinally to the left (Figure 1) by the inner face of the aperture 5 and the pin 6 and is prevented from moving in the other direction (to the right) by the abutment 13 where its notch 15 contacts the cutting face 16 of the bit 17. In the drawing we have illustrated a bit with the faces having a non-parallel surface as is illustrated in Patent No. 2,039,747 issued May 5, 1936 to E. P. Stenger et al., but we do not limit ourselves to the specific bit. A bit of similar cross section with parallel cutting surfaces can likewise be mounted in the same type of holder and cradle with about equal efficiency.

In order to change the bit 17 end for end after one point has become dull it is merely necessary to loosen the set screw 3 and to lift the holder a sufficient distance for the heel of the cutting face of the bit to clear abutment 15 on the cradle 10, after which the bit can be readily removed from the holder.

When it is found desirable to reverse the direction of the cutting machine, the chain is caused to travel in the opposite direction. When this is done bit 17 is brought into proper position by merely loosening set screw 3 and the whole device comprising the bit, bit holder and the cradle is removed from aperture 2 in bit block 1. It may then be reversed and reinserted after first removing the set screw 3 and reinserting it in its opposing hole.

Inasmuch as a great amount of strain is placed on the inner surface of the abutment 14 and on surface 15 and thus tending to quickly wear them, we have provided a hole 29 which pierces the abutment 14. A shim 21 having a stud 22 projecting therefrom as illustrated in Figure 7 may be positioned against the inner surface of the abutment 14 with the stud 22 inserted in the hole 29. This will take up for wear on the inner face of the abutment 14 and 15 as will be apparent from the drawing.

In the modification of the cradle shown in Figures 5 and 6, the cradle has two identically formed abutments 13 and 13a. These abutments are similar in configuration to the abutment 13 shown in Figure 4 and described above. In this modification the cradle itself may be reversed in relation to the bit and the bit holder 4. In this instance we provide a hole 20 in both the abutments 13 and 13a to retain the shim holding plug 22 if it becomes necessary to insert a shim due to wear.

In the modification illustrated in Figure 8, the abutting surface of the abutment 14 is inclined as is the rear face 4a of the head 4. By this construction a wedging action is created between the head 4 with its bit 17 together with the front and rear surfaces of the abutments 13 and 14. Inasmuch as the surface of the shank 8 which contacts the end of the set screw 3 slopes and thus a pulling tendency on the shank and the head is brought about, this feature together with the wedging action as described insures the setting of the cradle on the top of the bit block 1 and the tight setting of the bit carrying head within the cradle.

In the event it is desirable to make the bit 17 project further in relation to the bit block 1, we may encircle the shank 8 of the bit holder below the cradle and above the surface of the

bit block 1 with shims of varying thickness as shown in Fig. 9.

It is apparent that the aperture 5 of the bit holder as well as the position of the pin 6 may be differently configured in order to retain bits of different shape. It is also apparent that in the use of shims we may provide them of different thicknesses so that the amount of wear may be taken up no matter how little or how great. It is to be understood that different forms of our preferred form may be made without departing from the spirit of our invention.

Having thus described our invention, what we claim as new and desire to secured by Letters Patent is:

1. In combination with a bit, a bit block, a bit holder having a bit retaining aperture and a shank projecting into the bit block, a separate and removable cradle surrounding a portion of the holder and positioned on the block and under the active cutting point of the bit, said cradle having an abutment contacting the cutting face and opposing withdrawal of the bit from the bit holder.
2. In combination with a bit, a bit block, a bit holder having a bit retaining head and having a shank projecting and retained in the bit block, a separate and removable cradle surrounding said shank and positioned between the bit retaining head and the bit block, said cradle having an abutment contacting the cutting face and opposing withdrawal of the bit from the bit retaining head, the interior of the cradle and the bottom of the bit retaining head being beveled so that they slide within each other.
3. In combination with a bit, a bit block, a bit holder having a bit retaining aperture and having a shank projecting into the bit block, a separate and removable cradle surrounding said shank and positioned between the head of the bit holder and the bit block, said cradle having an abutment contacting the cutting face and opposing withdrawal of the bit from the bit holder, said bit holder and said cradle being reversible in said bit block.
4. In combination with a bit, a bit block, a bit holder having a bit retaining aperture, a shank projecting into the bit block, a cradle surrounding said shank and positioned between the head of the bit holder and the bit block, said cradle having an abutment contacting the cutting face and opposing withdrawal of the bit from the bit holder and a second abutment contacting the rear of the bit holder.
5. In combination with a bit, a bit block, a bit holder having a bit retaining aperture and a shank projecting into the bit block, a cradle surrounding said shank and positioned between the head of the bit holder and the bit block, said cradle having an abutment opposing withdrawal of the bit from the bit holder and a second abutment contacting the rear of the bit holder, a shim placed between said second abutment and the rear of the bit holder and having a projecting positioning stud journaled in an aperture in said second abutment.
6. In combination with a bit, a bit block, a bit holder having a bit retaining aperture and a shank projecting into the bit block, a separate and removable cradle surrounding said shank and positioned between the bit holder and the bit block, said cradle having an abutment opposing withdrawal of the bit from the bit holder and a second identical abutment contacting the rear of the bit holder so that said cradle may be re-

versed in reference to said bit holder and bit block.

7. In combination with a bit, a bit block, a bit holder having a bit retaining aperture and a shank projecting into the bit block, a cradle surrounding said shank and positioned between the bit holder and the bit block, said cradle having an abutment opposing withdrawal of the bit from the bit holder and a second identical abutment contacting the rear of the bit holder so that said cradle may be reversed in reference to said bit holder and bit block and both said abutments having a bit retaining groove.

8. In combination with a bit, a bit block, a bit holder having a bit retaining aperture and a shank projecting into the bit block, a separate and removable cradle encircling a portion of the bit holder and positioned between the head of the bit holder and the bit block, said cradle having an abutment which contacts a portion of the cutting surface of a retained bit in the holder and opposes removal of the same.

9. In a mining machine chain, a bit block, a bit holder having a bit retaining aperture and a shank projecting into the bit block, a separate and removable cradle encircling a portion of the holder, a set screw for holding said holder in place, and a cutter bit in said bit retaining aper-

ture and projecting angularly therefrom beyond the holder, the cutting face of said bit overlying and abutting said cradle and thereby limiting insertive movement of the bit holder into the bit block.

10. In combination with a multi-pointed bit having cutting faces lying in dihedral angles, a bit block, a bit holder having a bit retaining aperture and a shank projecting into the bit block, and a separate and removable cradle surrounding a portion of the holder and positioned on the block, and under the active cutting point of the bit, said cradle having an abutment engaging the active cutting face of the bit and opposing withdrawal of the bit from the bit holder.

11. In combination with a multi-pointed bit, a bit block, a bit holder having a bit retaining aperture and a shank projecting into the bit block, and a separate and removable cradle surrounding a portion of the holder and positioned on the block and under the active cutting point of the bit, said cradle having an abutment engaging the active cutting face of the bit and opposing withdrawal of the bit from the bit holder.
